TUNNELING SYSTEM

Stanley M. Mercier, Columbus, Ohio, and H. L. Myer, Mason City, Wash., assignors to The Jeffrey Manufacturing Company, a corporation of Ohio

Application December 28, 1935, Serial No. 56,578

5 Claims. (Cl. 214—41)

This invention relates to apparatus particularly adapted for digging tunnels and removing the excavated dirt.

An object of the invention is to provide an improved excavating and loading system for removing dirt in the digging of a tunnel.

Another object of the invention is to provide an improved type of train car loading conveyor adapted to be fed by a digging and loading machine, which will permit the said digging and loading machine to travel thereunder whereby it may be removed from a tunnel of restricted width without requiring removal of the train car loading conveyor.

15 Other objects of the invention will appear hereinafter, the novel features and combinations being set forth in the appended claims.

In the accompanying drawings,

Fig. 1 is a side elevational view of the tunneling system shown in a tunnel and comprising our invention;

Fig. 2 is an end elevational view of the tunnel and apparatus of Fig. 1;

25 Figs. 3 and 4, placed end to end along line A—A, comprise a side elevational view of the train car loading conveyor of our invention;

Fig. 5 is an enlarged elevational view of a detail of the device of Figs. 3 and 4 showing the pivotal mounting of the car loading conveyor on a gantry and the pivoted front or loading end thereof;

Fig. 6 is a transverse sectional elevational view taken on the line 6—6 of Fig. 5, looking in the direction of the arrows;

Fig. 7 is a transverse sectional view taken on the line 7—7 of Fig. 4, looking in the direction of the arrows;

Fig. 8 is a detail sectional view taken on the line 8—8 of Fig. 5, looking in the direction of the arrows, and

40 Fig. 9 is a piping diagram for the hydraulic piston motors.

As best seen in Figs. 1 and 2 of the drawings, our invention comprises a system for digging tunnels, the tunnel being indicated at 10. It often happens that a tunnel is desired to be dug which does not have sufficient width to permit the laying of two tracks side by side over which train cars and a digging and loading machine may travel. It is desirable, however, to provide for the successive loading of a series of cars of a train from a digging and loading machine, yet to provide for the ready removal of the digging and loading machine whereby it may be periodically oiled and greased or removed from the tunnel for repair without requiring the removal of the load-

ing conveyor which loads the cars of the train. Our system and our novel loading conveyor provides for the ready removal of the combined loading and digging machine without requiring any removal of said loading conveyor from the tunnel. 5

As illustrated in Figs. 1 and 2, as the tunnel operation progresses, two pairs of tracks 11 and 12 are laid. The tracks 11 are adapted to support the cars 13 which haul away the dirt or other material excavated in forming the tunnel. For 10 digging the tunnel and for removing any dirt or other material dug or otherwise loosened by the tunneling operation adjacent the face of the tunnel, we provide a combined digging and loading machine 14 which may be of any well known 15 type. Purely as illustrative of the type of machine which may be here employed, we may employ a device like that disclosed in the patent to E. C. Morgan, No. 1,663,917, dated March 27, 1928. Such a combined digging and loading machine will be employed to dig material from the tunnel face or to gather otherwise loosened material and to convey it rearwardly thereof.

In order to permit the loading of a large number of cars 13 we provide within the tunnel a 20 combined loader and conveyor 15 which is of novel construction and comprises an important feature of our system as well as a novel machine which alone comprises a feature of our invention. The specific structure of the combined loader and conveyor 15 will be described in detail herein- 25 after, but for the present it is sufficient to note that it comprises a main boom 16 and a pivotally connected loading section 17. The pivotally connected loading section 17 may be lowered where- 30 by it will be in position to receive material dis- charged from the rear conveyor of the combined digging and loading machine 14, or it may be sufficiently elevated, as illustrated in Fig. 1, to 35 permit the said combined digging and loading ma- 40 chine 14 to pass freely thereunder.

As best illustrated in Fig. 2 of the drawings, the combined loader and conveyor 15 is mounted upon the tracks 12 which are positioned outside of the tracks 11, and is supported upon appropriate gantries 18 and 19 to permit free move- 45 ment of both the cars 13 and the combined digging and loading machine 14 thereunder. It will thus be evident that the combined loader and conveyor 15 may be employed to load a plurality 50 of cars 13 successively while being fed from the digging and loading machine 14, yet will readily permit of movement of the digging and loading machine 14 thereunder so that it can be removed 55 from the tunnel for any desired purpose with-

cut requiring the removal of the relatively large loader and conveyor 15 from said tunnel.

The detailed structure of the combined loader and conveyor 15 is illustrated in Figs. 3 to 9, 5 inclusive, and reference is made to those figures in connection with the following description of the structure which provides for the above noted capabilities of operation. As best seen in Figs. 3 and 4, the main boom 16 comprises an elongated framework built up of the usual angles and side plates with appropriate reinforcing diagonal angle members and gusset plates. Within the boom 16 there is formed a trough 20 (Fig. 6) within which material is adapted to be guided. 10 The front end of the boom 16 is supported upon a gantry 18 which comprises a pair of spaced up-standing frames 21, 21, best seen in Fig. 2, which are mounted upon wheels 22 adapted to ride upon the track rails 12. Extending transversely between the rails 12 we provide a bolster 23 formed by a pair of spaced channel members 24 (Fig. 5) and a top plate 25. These members may be rigidly attached as by welding or riveting.

In connecting the boom 16 to the gantry 18 it is desirable that both relative pivotal and relative lateral movement be provided therebetween. This is necessary in case the loader and conveyor 15 is to be used in a curved tunnel, for sometimes, due to the great length thereof, it will be necessary not only for the boom 16 to pivot with respect to the gantry 18 but for it to slide laterally with respect thereto to avoid its striking the walls of the tunnel. To provide for this relative pivotal movement and lateral movement a pin 26 is carried by the bolster 23. Resting upon the top plate 25 of said bolster 23 and forming a bearing plate for the boom 16, there is a bearing plate 27 attached to the side walls of said boom 16 as by welding. Appropriate channel member 28 may 30 be provided to reinforce the bearing plate 27. Between the channel member 28 and the bearing plate 27 we may also provide a filler plate 29. An elongated transversely extending slot 30 is provided in the bearing plate 27, filler plate 29, 40 and channel member 28, through which the pin 26 extends whereby both pivotal and lateral movement of the boom 16, with respect to the gantry 18, is provided. It will be noted that the top of the pin 26 is retained in the groove 30 by a riveted head 31, and the bottom thereof is retained on the bolster 23 by a washer 32 held by a cotter pin and co-operating with an apertured plate 33. Positioned upon the head 31 of pin 26 is a shield 34 which prevents contact between the 50 belt of the conveyor and said head 31. Said shield 34 may be provided with an aperture 35 to permit ready removal of the pin 26. It may also be noted that the boom 16 is provided with angle members 36 which pass beneath the bolster 23 and thus the bolster 23 is totally encased by 60 elements of the boom 16.

Adjacent the rear end of the boom 16 there is provided the previously mentioned gantry 18 which has the same structure as the gantry 18 65 and is connected to the boom 16 in exactly the same manner. Detailed description of this gantry will therefore be unnecessary.

Pivotedly attached to the forward end of the boom 16 is the loading section 17, the pivotal connection being about a horizontal axis and being effected as illustrated in Fig. 8. As is here illustrated, the main boom 16 carries on each side wall a journal bearing 37 adapted to receive a journal bearing cup 38 carried by the side walls of 70 the loading section 17. Journaled within the cup

38 is a shaft 39 carrying a belt drum 40 adapted to guide and support a continuous conveyor belt 41 which travels throughout the combined loader and conveyor 15.

Within both the boom 16 and loading section 5 17 there are provided spaced rollers 42 adapted to support the conveyor belt 41. As best seen in Fig. 3 of the drawings, a head pulley 43 is provided adjacent the rear end of the boom 16 over which the belt 41 travels and discharges its material. Spaced rearwardly of the pulley 43 is a driving motor 44 which may be connected to said pulley 43 by any well known appropriate drive means, such as a drive chain and sprocket mechanism. 15

It will be evident that the material carried by the belt 41 will be discharged to the cars 13 at a position intermediate the motor 44 and the pulley 43. Return guide rollers 45 will be provided for guiding and supporting the lower run of the 20 belt 41.

As best seen in Fig. 7, the loading section 17 is provided with trough forming side plates 46 which retain material on the belt 41. Adjacent the forward end of the loading section 17 we provide a 25 hopper 47 adapted to be fed with material from the combined digging and loading machine 14, illustrated in Fig. 1. This hopper is formed with side walls 48 and an end wall 49 all of which are split and hingedly connected as illustrated at 30 50 and 51, respectively. This hinged formation of the hopper 47 provides for the elevation of the forward end of the loading section 17 to within a relatively short distance of the top of the tunnel and provides increased clearance, permitting 35 free travel of the digging and loading machine 14 thereunder. That is, as is clearly illustrated in Fig. 1 of the drawings, by swinging downward the top portion of the walls 48 and 49, increased elevation of the forward end of the loading section 17 is provided. When the loading section 17 is in a lowered position, as illustrated in Fig. 4, in which it is adapted to be fed by the digging and loading machine 14, the side walls 48 and end wall 49 will be in the position illustrated in Fig. 4 40 45 to form a large hopper of sufficient size for satisfactory operation.

It will be evident that as material is discharged from the digging and loading machine 14 and falls into the hopper 47, it will drop with appreciable force on the belt 41. In order to provide for the incident strain, the belt 41 is adapted to travel on another relatively short endless belt 52 which travels between the pulleys 53 and 54, seen in Fig. 4. The lower face of the upper run of belt 55 52 will slide on a metal plate 55 supported upon longitudinally extending planks 56 carried between transversely extending members 57 which are supported upon rubber cushion blocks 58 on the side frames of the loading section 17. Supporting rollers 59 support the lower run of the two belts 41 and 52, and guide rollers 60 keep them in proper position.

As illustrated in Fig. 4 of the drawings, the forward end of the loading section 17 is provided 65 with shoes 61 adapted to rest upon the rails 12 to support said forward end of said loading section 17. To provide for the raising and lowering of the loading section 17 about its pivot point, we provide a pair of hydraulic cylinders 62, 62, one 70 on each side of the boom 16, with which co-operate pistons 63, 63 adapted for movement by hydraulic pressure. As best seen in Fig. 9 of the drawings, pistons 63, 63 are always operated in unison and may be controlled by a valve 64 which 75

controls the flow of hydraulic fluid from any desired source which, for example, may be located outside of the tunnel and may be connected to the pipe 65 as by a flexible rubber hose. The valve 64 may, of course, be operated to move the pistons in either direction and to lock them in any position to which they are moved.

Attached to the pistons 63 are piston rods 66, 66 to the free ends of which are attached flexible cables, one of which is seen at 67 in Figs. 1 and 4. The cables 67 are reeved over pulleys 68 carried on the boom 16 and attached to the loading section 17. Movement of the pistons 63, 63 will thus raise or lower the loading section 17 in a pivotal movement about its connection to the boom 16, in an obvious manner.

In the operation of the system to perform digging of the tunnel and removal of the material, the combined digging and loading machine 14 may be employed to dig on the face of the tunnel or to gather material otherwise loosened at said face. This material will be conveyed rearwardly by said digging and loading machine 14 and discharged into the hopper 47 of the combined loader and conveyor 15, the hopper 47 being, of course, in the lowered position as illustrated in Fig. 4. The conveyor belt 41 will, of course, be driven continuously by the motor 44 and will convey any material received by the hopper 47 and discharge it into one of the cars 13. When the operation starts the greatest possible number of cars 13 will be positioned beneath the boom 16 and as the cars become loaded, successive empty cars will be hauled into position to be filled by the loader and conveyor 15 until all of the cars 13 are filled. Thereafter, cars 13 will be hauled from the tunnel and dumped, after which they will be returned for refilling.

When it is desired to shut down the operation of the system and to grease, inspect or repair the digging and loading machine 14, the valve 64 will be operated to elevate the loading section 17. This will permit said digging and loading machine 14 to travel rearwardly on its tracks 11 beneath said loader and conveyor 15. In elevating the loading section 17 it may be necessary to drop the upper pivoted portions of the walls 48 and 49 thereof in order to provide adequate clearance for said digging and loading machine 14. If the tunnel has appreciable height, this may not be necessary.

It will thus be seen that we have provided a system in which the combined digging and loading machine 14 may be readily removed from the tunnel for any desired purpose without requiring removal therefrom of the exceedingly large loader and conveyor 15 which has no self-propelling operating means. This is also accomplished without requiring two pair of side by side parallel tracks which oft-times can not be accommodated by the size of the tunnel under construction.

The novel construction of the combined loader and conveyor 15 not only permits of ready removal of the digging and loading machine 14, but also provides for its use in a curved tunnel by virtue of the pivotal and lateral adjustment provided between the boom 16 and the gantries 18 and 19 thereof.

It should be particularly noted that the hopper 47 is of extremely large capacity. This is accomplished by the pivoted walls 48, 49 which also provide satisfactory clearance when elevated. Due to this large capacity of the hopper, it is possible to operate the digger and loader 14 substantially continuously while discharging material to fill the

cars 13 intermittently. That is, the dug material may accumulate in the hopper 47 while the cars 13 are being unloaded and the conveyor belt 41 idle, thus increasing the total capacity of the system to a maximum, as determined solely by the capacity of the digger and loader 14.

Obviously those skilled in the art may make various changes in the details and arrangement of parts without departing from the spirit and scope of the invention as defined by the claims hereto appended, and we therefore wish not to be restricted to the precise construction herein disclosed.

Having thus described and shown an embodiment of our invention, what we desire to secure by Letters Patent of the United States is:

1. In a tunneling loader, the combination with spaced gantries, of an elongated boom mounted on said gantries, a material receiving section pivoted to said boom on a horizontal axis, belt means on said boom and receiving section adapted to convey material, and means for raising and lowering said material receiving section, said gantries co-operating with said material receiving section to provide clearance beneath said conveyor to allow machinery to pass thereunder when said receiving section is raised, said receiving section being adapted to receive material when in a lowered position, said receiving section having a material receiving hopper at its free end, the walls of which are hinged intermediate their tops and bottoms whereby the maximum clearance provided by said receiving section may be increased.

2. In a tunneling loader, the combination with spaced gantries, of an elongated boom mounted on said gantries, a material receiving section pivoted to said boom on a horizontal axis, belt means on said boom and receiving section adapted to convey material, and means for raising and lowering said material receiving section, said gantries co-operating with said material receiving section to provide clearance beneath said conveyor to allow machinery to pass thereunder when said receiving section is raised, said receiving section being adapted to receive material when in a lowered position, said receiving section having a material receiving hopper at its free end, the walls of which are hinged whereby the maximum clearance provided by said receiving section may be increased.

3. In a tunneling loader, the combination with spaced end supporting means, of an elongated boom mounted on said spaced supporting means, a material receiving section pivoted to said boom on a horizontal axis, belt means on said boom and receiving section adapted to convey material, and means for raising and lowering said material receiving section, said spaced supporting means co-operating with said material receiving section to provide clearance beneath said conveyor to allow machinery to pass thereunder when said receiving section is raised, said receiving section being adapted to receive material when in a lowered position, said receiving section having a material receiving hopper at its free end, the walls of which are hinged whereby the maximum clearance provided by said receiving section may be increased.

4. In a tunneling loader, the combination with an elongated conveyor including an endless belt and having a pivoted end adapted to be raised and lowered, of a material receiving hopper on said lowered end adapted to be filled with material, cushion belt supporting means below said hopper, supporting means for said conveyor adapted to support it in an elevated position to

- 5 permit a train of cars to pass thereunder for loading thereby, said supporting means including gantries at each end thereof having track riding wheels on opposite sides of said conveyor providing for ready movement of said conveyor longitudinally, means mounting said conveyor on said gantries to permit both pivotal lateral movement of said conveyor relative thereto, and motor operated means for raising and lowering 10 said hopper by swinging said pivoted end of said conveyor to provide clearance for machinery to pass under the entire length of the conveyor.
- 10 5. In a tunneling loader, the combination with an elongated conveyor including an endless belt and having a pivoted end adapted to be raised and lowered, of a material receiving hopper on
- 15

5 said lowered end adapted to be filled with material, cushion belt supporting means below said hopper, supporting means for said conveyor adapted to support it in an elevated position to permit a train of cars to pass thereunder for loading thereby, said supporting means including gantries at each end thereof having track riding wheels on opposite sides of said conveyor providing for ready movement of said conveyor longitudinally, and motor operated means for 10 raising and lowering said hopper by swinging said pivoted end of said conveyor to provide clearance for machinery to pass under the entire length of the conveyor.

STANLEY M. MERCIER. 15
H. L. MYER.
